UNITED STATES PATENT OFFICE.

JAMES MADISON JACKSON, OF PARKERSBURG, WEST VIRGINIA.

SPRING-OILING CLIP.

Application filed September 28, 1926. Serial No. 138,260.

This invention relates to a spring rebound clip and oiler and has special reference to an improved oiler clip of the type shown in my prior Patent No. 1,570,746 issued to me January 26, 1926, for shackle bolt and spring lubricating means.

One important object of the invention is to so improve the construction of the oiler clip shown in said patent that it may be readily applied to a spring without the necessity of disconnecting any part of the spring from the vehicle on which it is used.

A second important object of the invention is to so improve said oiler clip that it may be used with or without my shackle bolt shown in said patent.

A third important object of the invention is to provide improved means whereby the clip may be tightly clamped to the spring.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of a portion of a vehicle frame and its attached spring and showing the improved clip as applied thereto in using my shackle bolt.

Figure 2 is a perspective view of the device removed from the spring and supplied with an oil cup.

Figure 3 is a side elevation of the main portion or body of the clip.

Figure 4 is a side elevation of the cover or cap portion of the clip.

Figure 5 is a plan view of the body.

Figure 6 is an inverted plan view of the cap.

Figure 7 is a section of the clip assembled and showing the same applied to a spring.

Figure 8 is a view showing a special bolt used herewith in elevation and section.

This invention consists of two principal parts, a body and a cap and the body is provided with a base portion 10 from each side of which there extends a leg 11, said legs being usually, for the ordinary type of spring, arranged at right angles to the base. Both the base and legs are internally channeled so as to receive a strip 12 of felt or

other suitable oil absorbing capillary material. Centrally of the exterior of the base is provided a boss 13, the base and boss having a threaded opening for a set screw 14 whereon is a jam nut 15. It will be seen that the leg portions of the felt strip terminate in spaced relation to the legs 11 and that just above the ends of said strip each leg 11 is provided with a transversely extending slot 16, the purpose of which will be presently explained.

The cap is of somewhat similar arrangement being of such dimensions as to fit over the ends of the legs and having a pair of side walls 17 each having a slot 18 therein which, when the device is assembled, registers with a respective slot 16. On the outer face of one side wall is formed a face ratchet 19 which surrounds the slot in that face. This cap is like the body, provided with a felt strip 20 having legs which, upon the parts being brought together, abut the leg portions of the strip 12 so that a spring 3 enclosed by the two parts is entirely surrounded by the felt.

The bolt which holds these parts together is provided with a head 21 having its under face serrated to form a face ratchet 22. The bolt body 23 is of oblong form in cross section and is of slightly less size than the openings 16 and 18 so that it may pass therethrough. Adjacent the head the body is reduced to form a cylindrical neck 24 which rests in the openings 16 and 18 at one side of the neck, the body being similarly reduced at the end and threaded as at 25, the reduced end resting in the other openings 16 and 18. The usual nut 26 is provided for this bolt. By this means the device, when assembled, may be caused to grip the spring tightly since the bolt body may be inserted in position to lie flat on the spring and then forcibly rotated to bring the longer diameter of the body as nearly vertical to the spring as possible, the face clutches engaging to hold it in this position upon tightening of the nut 26.

The cap is provided with a suitable threaded opening in which may be screwed an oil cup 27 or the end of my oil feed pipe 29.

By thus applying the new clamp several of the leaves of the spring may be clamped together to act as a unit on the rebound instead of having to depend on a single leaf for this purpose. Moreover, the set screw

serves, by engagement with a center punched or drilled depression in the spring, to prevent slipping of the clip.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

15 Having thus described the invention, what is claimed as new, is:

1. In combination, a spring clip adapted to surround a spring, a bolt passing through the clip revolvably and having a central cam-like portion adapted to rest on the spring and exert pressure thereon upon rotation in one direction, and means to hold the bolt in rotated pressure applying position.

2. In combination, a spring clip adapted to surround a spring, a bolt passing through the clip revolvably and having a central cam-like portion adapted to rest on the spring and exert pressure thereon upon rotation in one direction, and means to hold the bolt in rotated pressure applying position, said means including cooperating ratchet devices on the bolt and clip respectively.

3. In combination, a spring clip including a body portion having an open side and adapted to engage around three sides of a spring, a cap fitting the open side of the body and adapted to cover the remaining side of the spring, said body and cap having alined bolt receiving openings, a bolt passing through said openings to hold the cap on the body and provided with a central cam like portion adapted to bear against the last mentioned side of the spring and apply pressure thereto upon rotation, and means to hold the bolt in rotated pressure applying position.

4. In combination, a spring clip including a body portion having an open side and adapted to engage around three sides of a

spring, a cap fitting the open side of the body and adapted to cover the remaining side of the spring, said body and cap having alined bolt receiving openings, a bolt passing through said openings to hold the cap on the body and provided with a central cam like portion adapted to bear against the last mentioned side of the spring and apply pressure thereto upon rotation, and means to hold the bolt in rotated pressure applying position, said means including cooperating ratchet devices on the bolt and clip respectively.

5. In combination, a spring clip including a body portion having an open side and adapted to engage around three sides of a spring, a cap fitting the open side of the body and adapted to cover the remaining side of the spring, said body and cap having alined bolt receiving openings, a bolt passing through said openings to hold the cap on the body and provided with a central cam like portion adapted to bear against the last mentioned side of the spring and apply pressure thereto upon rotation, and means to hold the bolt in rotated pressure applying position, and a set screw screwed through the body and alined with said cam like portion.

6. In combination, a spring clip including a body portion having an open side and adapted to engage around three sides of a spring, a cap fitting the open side of the body and adapted to cover the remaining side of the spring, said body and cap having alined bolt receiving openings, a bolt passing through said openings to hold the cap on the body and provided with a central cam like portion adapted to bear against the last mentioned side of the spring and apply pressure thereto upon rotation, and means to hold the bolt in rotated pressure applying position, said means including cooperating ratchet devices on the bolt and clip respectively, and a set screw screwed through the body and alined with said cam like portion.

In testimony whereof I affix my signature.

JAMES MADISON JACKSON.
